UNITED STATES PATENT OFFICE.

EDWARD F.-G. GIBBS, OF WASHINGTON, DISTRICT OF COLUMBIA.

REVERSIBLE BORING-BAR HOLDER.

1,308,282.

Specification of Letters Patent.

Patented July 1, 1919.

Application filed October 15, 1915. Serial No. 56,000.

To all whom it may concern:

Be it known that I, EDWARD F.-G. GIBBS, a citizen of the United States, residing at Washington, in the District of Columbia, 5 have invented certain new and useful Improvements in Reversible Boring-Bar Holders, of which the following is a specification.

My invention relates to that class of boring bar holders which, the tool post being removed, are bolted directly to the tool seat of an ordinary engine lathe, and hold the bars, which, in turn, hold the inserted cutters or tools used in boring metals. It is 10 hereinafter fully described, shown in the accompanying drawings, and then specifically defined in the appended claims.

The specific object of this invention is to obtain a one-piece holder, of the character 20 described, which is very rigid, simple, inexpensive, receives boring bars of various diameters, in horizontally elongated bar-holding apertures, and which is adapted to lathes whose spindle centers have various elevations or distances, above their respective tool seats.

I obtain these objects by means of what I would call a boring block, preferably a hollow block, or box, of proper form and 30 dimensions, from which I obtain a series of fixed elevations, or distances of aperture-centers above block bottoms, which, elevations, increase or diminish at a uniform ratio by reversing the block both longitudinally and vertically, (end for end and upside down); the complete mechanism of 35 which is illustrated in the accompanying drawings, which form a part of this specification, and in which drawings—

40 Figure 1 is a plan view of the holder complete, holding a boring bar with cutter in working position.

Fig. 2 is a side elevation showing a section of the boring bar.

45 Fig. 3 is a central sectional view on line $\alpha\alpha$ of Fig. 1.

Fig. 4 is an end view.

Fig. 5 is a plan view of an elevating liner.

Fig. 6 is a side elevation of the said liner.

50 Reference now being had to the details of the drawings by letter, in which similar letters refer to similar parts throughout the several views—

A designates the holder proper or block, 55 α the bar-holding apertures, α^2 the main opening or hollow of the block, α^3 the set

screw lugs, α^4 the numerical characters which express the respective elevations in inches, while α^5 designates the female centers which indicate the horizontal center lines of the 60 apertures.

B designates the king bolt by which the holder is bolted to the tool ring seat.

C designates the bar-pressing set screws by which the bar is clamped in working position. 65

D designates the boring bar.

E designates the inserted cutter.

F designates the elevating liner.

Block A, being a metallic casting, I eliminate the original cost of a large amount of superfluous metal, lighten the holder, facilitate manufacture and obtain a mechanical advantage by internal coring. 70

From Figs. 1, 2 and 3 it is seen that a 75 horizontally elongated, bar-holding (cored) aperture α whose apex is turned toward the king bolt B, passes transversely through each end of the block at right angles to its sides, and parallel to its top and bottom surfaces 80 and to each other.

The said apertures, α , are connected by another (cored) opening, the main hollow of the box α^2 , which, constricted at both ends, extends through the entire length of the 85 block and through the apertures as shown in Figs. 1, 2, 3, and 4.

Figs. 1, 2 and 3 show that the box or block A, being cored out between its walls, the inserted bar, E, pressed by set screws, C, bears 90 against the two side walls only; thus advantageously separating the bearing points to the greatest extent.

It is further shown that set screws C, having screw-thread engagement in lugs, α^3 , 95 enter the apertures and force the inserted bar E, back toward, and very near the king bolt, B. This and the close proximity of the apertures to the king bolt is designed to bring the strain receiving point of cutter, D, as near directly in front of the king bolt as possible for the sake of rigidity. 100

Also the bar-holding apertures, α , are elongated horizontally rather than vertically in order that the centers of bars of various 105 sizes will fall in the same horizontal plane.

It is understood that a boring bar in operation should maintain an elevation in which its axial center moves in the same horizontal plane as that of the axial center of 110 the lathe spindle or a little lower.

Using the actual working drawing dimen-

sions to illustrate the principle involved, it is to be seen from Figs. 2 and 3 that when the block is in the position shown in Fig. 1, the elevation of the bar center, or the bar, is 5 $1\frac{3}{8}$ inches above the bottom of the holder, which elevation is indicated by the numerical character $1\frac{3}{8}$ in Fig. 1, designated by a^4 cast or stamped in the surface of the block over the bar; when it is reversed longitudinally, 10 (end for end) the elevation of the bar is $1\frac{1}{2}$ inches, and this fact is indicated by the numerical character $1\frac{1}{2}$ also designated by a^4 , cast on the top of the block over the bar; the block now being reversed vertically, (up- 15 side down) the elevation of the bar is $1\frac{5}{8}$ inches, which fact is indicated by the proper character on the surface of the block above the bar; and when it is again reversed, longitudinally, the fourth elevation of the bar 20 is $1\frac{3}{4}$ inches and the fact indicated by the proper character on the block above the bar. Thus when the elevation of the lathe center is known the holder can be intelligently set, or the characters may be integral numbers 25 and refer to certain lathes of that number.

However, a series of four elevations, increasing at the ratio of one-eighth of an inch each is thus obtained in a practical one-piece holder, which will accommodate most 30 of the lathes in general use, but not all. The range of elevations, in my opinion, should cover about one inch, for a universal holder. Nor is it practical to increase the ratio of increase from one-eighth to one 35 quarter of an inch, nor is it practical to rest the holder on four surfaces instead of two in reversing it, nor is it desirable to use elevating liners at all, especially thin ones, because they must be detached, and thin liners 40 impair rigidity. I adopt, therefore a half-inch liner, whose thickness ($\frac{1}{2}$ inch) added to the lowest elevation of the block ($1\frac{3}{8}$ inches) is equal to its highest elevation ($1\frac{5}{8}$ inches) plus the ratio of increase ($\frac{1}{8}$ inch). 45 In other words, its thickness is such as to maintain the ratio of increase.

It is to be seen that the minimum and maximum elevations are vertical opposites and that the sum of their elevations is equal 50 to the sum of the two intermediate elevations; thus it is that the so-called top and bottom surface lines shown in Figs. 2 and 3 are parallel.

Female centers, a^5 , shown in Figs. 1 and 2, 55 denote the horizontal center lines of the apertures, a and are used in connection with the tail stock center of the lathe.

In cases where only one or two elevations are required I effect economy, both in manufacture and metal by using a hollow block with only one bar holding aperture, which reverses vertically only.

Rigidity may be increased in both cases by employing two king bolts, one located 65 near each vertical wall. This could not be

properly done if the last described block was solid and had set screws entering the aperture from the rear end.

Having thus fully described my invention, I submit the following claims:

1. A reversible boring bar holder, comprising a block having two similar, horizontal, vertically opposite, bearing surfaces, one of which is adapted to bear on the tool seat of an engine lathe, while the other is borne 75 upon by a king bolt nut, and vice versa; having a transverse, horizontal, horizontally elongated, bar holding aperture through one end, whose apex is turned toward the king bolt, and is unequally distanced between the said horizontal bearing surfaces; and having also a vertical king bolt passing through the said bearing surfaces; and horizontally disposed lugs, through which bar pressing set screws enter the said aperture; all substantially as set forth.

2. A reversible boring bar holder, comprising a hollow block having two similar, horizontal, vertically opposite, bearing surfaces adapted to bear on the tool seat of an engine lathe; having a transverse, horizontal, bar holding aperture through one end, unequally distanced between the said horizontal bearing surfaces, and connected with the main hollow of the block, between its side walls; and having also means for clamping the said block to the tool seat of an engine lathe; and means for clamping a boring bar in the said aperture; all substantially as set forth.

3. A reversible boring bar holder, comprising a hollow block having two similar, horizontal, vertically opposite, bearing surfaces adapted to bear on the tool seat of an engine lathe; having a transverse, horizontal, horizontally elongated, bar holding aperture through its end, whose apex is turned toward the king bolt, unequally distanced between the said horizontal bearing surfaces, and connected with the main hollow of the block between its side walls; and having also horizontally disposed lugs through which bar pressing set screws enter the said aperture; and means for clamping the said block to the tool seat of an engine 115 lathe; all substantially as set forth.

4. A reversible boring bar holder, comprising a hollow block having two similar, horizontal, vertically opposite, bearing surfaces adapted to bear on the tool seat of an engine lathe; having a transverse, horizontal bar holding aperture through each end, each aperture being unequally distanced between the said horizontal bearing surfaces, connected with each other through the main hollow of the block; and entered by bar pressing set screws; and a vertical king bolt passing through the said horizontal bearing surfaces; all substantially as set forth.

5. A reversible boring bar holder, com-

- prising a block having two similar, horizontal, vertically opposite bearing surfaces adapted to bear on the tool seat of an engine lathe; having a transverse, horizontal, bar holding aperture through each end, each aperture being unequally distanced between the said horizontal bearing surfaces, and differing with each other in elevation to an extent equal to the difference between the two intermediate elevations of the block; means for clamping boring bars in the said apertures; and a vertical king bolt passing through the said bearing surfaces; all substantially as set forth.
6. A universal boring bar holder, comprising a reversible block having two similar, horizontal, vertically opposite, bearing surfaces adapted to bear on the tool seat of an engine lathe; having a transverse, horizontal, bar holding aperture through each end, the said apertures differing with each other in elevations to an extent equal to the difference between the two intermediate elevations of the block; in combination with an elevating liner whose thickness added to
- the lowest elevation of the block, is equal to the highest elevation of the block plus the difference between the two intermediate elevations; means for clamping the said holder to the tool seat of an engine lathe; and means for clamping boring bars in the said apertures; all substantially as set forth.
7. A reversible boring bar holder, comprising a block having two similar, horizontal, vertically opposite bearing surfaces adapted to bear on the tool seat of an engine lathe; having a transverse bar-holding aperture through each end; unequally distanced between the top and bottom surfaces, the minimum and maximum elevations being vertically opposite to each other; and means for clamping the said block to the tool seat of an engine lathe; all substantially as set forth.

In testimony whereof I affix my signature in presence of two witnesses.

EDWARD F-G. GIBBS.
